UNITED STATES PATENT OFFICE.

CHESTER C. ECKHARDT, OF ROCHESTER, NEW YORK.

PRIMER AND HUMIDIFIER FOR INTERNAL-COMBUSTION ENGINES.

1,375,496.

Specification of Letters Patent. Patented Apr. 19, 1921.

Application filed April 25, 1919. Serial No. 292,705.

To all whom it may concern:

Be it known that I, CHESTER C. ECKHARDT, of Rochester, in the county of Monroe and State of New York, have invented 5 certain new and useful Improvements in Primers and Humidifiers for Internal-Combustion Engines; and I do hereby declare the following to be a full, clear, and exact description of the same, reference being had 10 to the accompanying drawings, forming a part of this specification, and to the reference-numerals marked thereon.

This invention relates to auxiliary devices for attachment to internal combustion engines, and, more particularly, to devices of the variety employed to modify the fuel charges, or to supply auxiliary charges for the engine, one object of the invention being the provision of an attachment of this nature adapted for a variety of uses, and of simple and inexpensive construction, convenient to operate and readily applicable to any internal combustion engine.

Another object is to provide a device of 25 this character which may be used for supplying combustible, decarbonizing or other liquid or vapor charges to the engine, or for humidifying the air supply or for other purposes, and which is conveniently adaptable 30 to these various uses. To these and other ends the invention resides in certain improvements and combinations of parts all as will be hereinafter more fully described, the novel features being pointed out in the 35 claims at the end of the specification.

In the drawings:

Figure 1 is a side elevation, partly sectional, of a portion of an automobile including the engine, dash and instrument boards, showing the invention applied thereto;

Fig. 2 is a section on the line 2—2 of Fig. 1, showing the container of the attachment;

Fig. 3 is a front view of a portion of the 45 attachment, showing the container and valve;

Fig. 4 is a fragmentary detail, partly in section, of the valve and piping.

Similar reference numerals throughout 50 the several views indicate the same parts.

This invention is applicable to any variety 55 of internal combustion engines, whether for marine, stationary or vehicular use and the embodiment at present preferred, as best applying the principles involved, is shown in Fig. 1 applied to an automobile of which the engine is denoted by 10, having the usual

intake manifold 11 and a dashboard 12 and instrument board 13. The invention comprises a container 14 attached to the forward 60 side of the dash by means of lugs 15, the bottom of the container, preferably, being formed with a tube 16 having a threaded bore 17. Within the container is a tube or conductor 18 provided adjacent its top with 65 lateral openings 19 communicating with the interior of the tube and having a threaded lower end 20 adjustably screwed into the upper end of tube 16. The threaded portion 20 of the conductor is provided with lateral 70 openings 21 communicating with the interior of the tube 18 and the conductor is formed with the stop shoulder 22 adapted to engage with the upper end of tube 16 when the conductor is fully inserted in the latter. 75 The upper end of the conductor is provided with a slot 23 for engagement with a tool, if necessary, for turning the conductor to adjust it in tube 16.

The top 24 of the container carries a depending tube 25 communicating at its lower end 26 with the container adjacent the bottom of the latter and this tube extends above the top of the container where it is threaded and provided with a threaded closure cap 80 27, the threaded portion of the tube being provided with openings 28 which may be placed in communication with the atmosphere by partially unscrewing the cap. The top of the container is also provided with a 85 filling opening 29 having a threaded flange 30 with which engages a threaded closure cap 31, the flange of the opening having formed therein a vent 32 which may be opened or closed to the atmosphere by adjustment of the cap as in the case of cap 27. 90

Connected with the lower end of tube 16 is a pipe 33 having formed therein a valve seat 34 to which is fitted a valve 35 held on its seat by a spring 36 pressing at one end 100 against the valve seat and at the other against a head 37 on a lug projecting from the valve. The latter has fixed thereto an arm 38 with which is pivotally connected a rod 39 extending through an opening 40 in 105 the dash board and through a guide tube 41 fixed to the instrument board of the automobile. Rod 39 carries at its end on the instrument board a finger-piece 42 which is moved to open and close the valve, the latter having 110 sufficient friction to maintain its adjusted position. Pipe 33 is connected below the valve by means of a coupling 43 with a tube 44 which extends forwardly to and com-

municates with the intake manifold of the engine at 45. The front of the container is provided with a transparent portion 46 through which the quantity of liquid contained may be observed.

The invention is useful for a number of different purposes, such, for example, as priming the engine in cold weather, supplying decarbonizing liquids and also lubricants to the cylinders, and humidifying the air of the charge. When used for priming, the container is partially filled with gasolene or other suitable priming fluid and conductor 18 is partially unscrewed to bring its openings 21 into communication with the liquid in the container, cap 27 being turned down to seal openings 28 and cap 31 being partially unscrewed to disclose vent 32, if necessary to relieve any vacuum that may form in the top of the container. With the parts so adjusted, when valve 35 is open, the liquid fuel in the container is drawn by the suction of the engine through the manifold into the cylinders, thus priming the engine to assist in starting it when cold.

Any fluid, of course, may be similarly used in the container, as, for instance, a decarbonizer such as kerosene, or similar agents or mixtures thereof, or a lubricant may in this manner be supplied to the cylinders. If it is desired merely to supply to the cylinders air heavily charged with an explosive vapor, such as that of refined gasolene, ether or similar fuel, conductor 18 is turned down to close openings 21, so that it communicates with the container through openings 19 above the liquid only, and cap 27 is partially unscrewed to expose openings 28, cap 31 being turned down to close the vent. With this arrangement of the parts, the container having been partially filled with the liquid, the suction of the engine draws air down the tube 25 and up through the liquid and thence through the conductor 18 to the engine, the air by this means being caused to bubble through the liquid and become heavily charged.

Another important use of the device is for the purpose of supplying humidified air to the engine, which, as well known, increases at times its efficiency of operation. For this purpose, the container is partially filled with water, cap 27 is unscrewed to expose openings 28 and conductor 18 is turned down to close openings 21, as before, so that air is drawn down tube 25, up through the water, down conductor 18 and to the engine.

The device may be adapted to any variety of internal combustion engines as by modifying the pipe connection 44 and the operating connection for valve 35. The construction is simple and inexpensive, and effective in operation, and the device is conveniently adaptable, by the adjustment of

the parts described, for the variety of uses for which it may be employed.

I claim as my invention:

1. An attachment for internal combustion engines comprising a container, an air inlet communicating therewith adjacent its bottom and means for closing the latter, a conduit communicating at one end with the intake of the engine and extending at its other end through said container and communicating with the latter adjacent its top, and means for opening and closing communication between said conduit and the bottom portion of said container.

2. An attachment for internal combustion engines comprising a container, a removable cap for filling the latter, an inlet communicating at one end with the atmosphere and at the other with the bottom of said container, means for closing said inlet, a conduit extending from the intake of the engine through said container and communicating with the top of the latter, and means for controlling communication between said conduit and the bottom of said container.

3. An attachment for internal combustion engines comprising a container, an air inlet communicating therewith adjacent its bottom and means for closing the latter, a conduit between said container and the intake of the engine and an extension on said conduit communicating with said container at its top and having means of adjustment for controlling communication between said conduit and the bottom of said container.

4. An attachment for internal combustion engines comprising a liquid container, controllable means for admitting air to said container at its bottom, a single conduit communicating at one end with the intake of the engine and at its other end with said container, and adjustable means for selectively supplying air to said conduit above the liquid of the container, or for supplying liquid thereto at a point adjacent the bottom of said container.

5. An attachment for internal combustion engines comprising a liquid container having an outlet adjacent its bottom, a conduit communicating with said outlet and with the intake of the engine, a conductor within said container communicating with the latter above the surface of the liquid therein and with said outlet, said conductor having adjustable means for controlling communication between said outlet and said container below the surface of the liquid therein, and controllable means for admitting air to said container below the surface of the liquid therein under the action of the partial vacuum transmitted by said conduit from the engine intake.

CHESTER C. ECKHARDT.
